UNITED STATES PATENT OFFICE

2,331,407

VAPOR HEATING SYSTEM

Charles F. Mahoney, Baldwin, Long Island, N. Y.,
assignor of one-half to Thomas A. Cetrino,
Brooklyn, N. Y.

Application March 1, 1941, Serial No. 381,339

2 Claims. (Cl. 237—9)

My invention relates to vapor heating systems, and more particularly to the class of heating systems where the vapor or steam is supplied through a single pipe to the various radiators, the latter having vent valves to allow the exit of air, and to prevent the escape of steam or water or other heating fluids therefrom, in other words to form a zone control system.

My invention is also an improvement in that type of valves that permits the air in the radiators to escape, but as soon as the heating fluid enters, the thermostatic element therein operates to close the same. The improvement includes a second thermostatic element that has been previously adjusted for a predetermined room temperature, and is arranged to prevent escape of radiator air while the room remains at the desired room temperature. This second thermostatic element, as has been noted, acts to hold a radiator venting valve closed if the room has been raised to the desired temperature, thus preventing the steam or other heating fluid from circulating and heating the room to an excessive temperature.

An object of the invention is to provide a heating system, whereby as the fuel burner control thermostatic unit operates, the fuel burner will start generating heat. The heating fluid forces the air out of the radiator if the room is below the desired temperature; the air passes through the first valve element, then through the second one also; but should the room be at the desired temperature the second valve element will prevent the circulation of any additional vapor by holding the valve closed until the temperature has been lowered.

A further object is to provide an economical, neat compact automatic controlling means that will perform its functions for which it was designed with efficiency and reliability.

And a further object is to provide independent automatic pressure or temperature controlled switches to control the complete system and prevent the fuel burner from operating until the heating fluid pressure and temperature has dropped to a predetermined point.

A still further object of the invention is to provide an automatic valve system that is adapted to be used as a zone heating control one pipe system; the valve system by its construction and operation will effect fuel saving and prevent over heating, by reason of the several elements being each adjusted so as to insure cooperation with each other to accomplish the desired effect.

Further aims, objects, and advantages of this

system will appear from a consideration of the description which follows with the accompanying drawing showing for purely illustrative purposes embodiments of this invention. It is understood, however, that the description is not to be taken in a literal sense, the scope of the description being defined in the appended claims.

Fig. 1 is a view of a vapor heating system showing my invention applied thereto.

10 Fig. 2 is an enlarged elevation with parts in section, a radiator with my control valve attached.

15 The heating system as shown in Fig. 1, consists of a boiler 10 with its main fuel burner and pressure control switch 11 and the forward part of the nose of a fuel burner 12, while extending from the top of the boiler is a single pipe 13 leading the heating fluid to the desired place or places; in the drawing three floors are shown or indicated each provided with one or more radiators 14, 15 and 16, and with my improvements attached. The fuel burner control thermostatic switch unit 17 is connected with starting wire b and the running wire a, and the wire a is the holding circuit for the relay control switch which operates the fuel burner 12 and c is a return wire for both the starting and running circuits.

20 Pressure or thermostatic delay starting switch 18 is a make and break switch which effects fuel saving and independently controls the fuel burner by allowing the burner to operate only when the pressure and temperature of the system is reduced. This control switch is so located that it is heated by the supply pipe 13, which may either 25 pass through the switch box 18 or be secured thereto, in other words, it opens on high temperature and closes on low temperature. As shown the switch 18 is in series with the wire a and thermostatic switch 17. The action of said switch causes the burner to delay until the temperature is reduced below the normal. Again, by 30 my new arrangement the device prevents waste of fuel by control of heating fuel pressure and temperature, and the device may be set so as to prevent the burner from operating until any desired low vapor pressure and temperature is 35 reached.

30 The action of the circuit control is as follows: The line voltage ground wire passes through limit switch 11, to terminal 1, then to primary side of transformer. And the line hot wire extends to terminal 2 then to other side of transformer, completing line circuit for transformer. The secondary voltage is for the operation of the relay transfer circuit action, also

for closing the high voltage circuit to load, be it fuel, coal or other heating means.

It should be noted that the secondary supply wire extends from terminal W, through the thermostat 17 by wire c, and returns by wire a, to terminal B, then to starting delay switch 18, and continues to relay and then returns to transformer secondary coil, and the other wire to secondary coil extends to terminal W, completing the starting circuit. The latter actuates the relay closing contacts g, h, e and d. e and d being the high voltage circuit to furnace, and g and h is the transfer circuit contacts for the holding or running circuit which is completed as follows: Starting at the starting terminal W, then to the thermostat 17 on the wire c and returning on wire b, to the terminal R, and from R, to contacts g and h, then to the relay, and returning as noted to secondary coil back to terminal W, which completes the holding circuit. It will be noted that operation of the relay for starting, can only take place when the delay switch 18, is in a closed position, that after any supply interruption of the electric current or opening of the limit switch 11, or the thermostat 17 that the second cycle of operation for again starting must pass through delay switch 18.

It should be noted in this wiring circuit to obtain the delay action as is intended, for instance, for a long delay action according to weather conditions, to use the thermo capacity of the heating equipment, radiators, pipes, etc., the delay starting switch circuit prevents in this case a second cycle of burner and heating operation, although the thermostat and other limit control switches are in a closed or starting position. That a second cycle of operation will take place only when the temperature of the radiators, pipes, etc., drop to a predetermined setting on the delay starting switch. The effect of the above action saves many hours of burner heating operation which results in a fuel saving and improves heating, prevents over riding of heat, and is also positive and automatic in its action. Because of the following facts; when the temperature drops the delay period is shortened, and as the temperature in or outside of a given building, the delay action time is increased, and this delay action time period varies between 15 minutes and one hour.

Referring now to Fig. 2, a portion of a radiator is shown at 20 with my invention attached, the latter comprising a rectangular perforated or wire housing 21 with an insulated partition 22 which divides the housing into two compartments 23 and 24 thus forming a room thermostatic control air vent valve (zone control). In compartment 23, I desire to place air vent 25 of any well known manufacture now on the market, said element having the usual connection 26 extending to the radiator through which the heating fluid is conveyed into the chamber 27 which contains a hollow cylindrical body 28, which contains a fluid that expands and thereby lifts the valve pin 25 to the port, and on contraction the fluid will cause the pin 25 to open the valve and permit the escape of air therefrom. The bottom of the body 28 which rests on a short pedestal 29 having adjusting means for regulating the distance that the body will move to operate the valve 25 to open or close the port 30. When the heating fluid enters said compartment it will close the port after having for a suitable time permitted the air in the system to escape.

To the top of the valve 25 is secured a short pipe 31, which conveys the air or heating fluid to its destination. As shown herein, the pipe is provided with a flaring seat 32 for the valve

5 33 carried by the thermostatic element 34 comprising suitable metallic strips that act on becoming heated or when cooled. As before noted this thermostatic element while shown in close proximity with the air vent valve 28, may be 10 placed at any suitable distance therefrom. It is preferable to place these two units side by side within a perforated or wire mesh housing 21 which may be wholly or partially closed, thus forming a room thermostatic control air vent 15 valve (zone controlled).

With a housing equipped with room temperature controlled air valves for the purpose of individual room control heating radiators, the thermostat in any room will operate to complete 20 the required circuit to control the operation of the burner motor so as to develop and maintain the desired steam pressure in the system. During such operation of the burner, the temperature controlled air valve permit the escape of 25 air from the radiators as required for proper room heating. In the system just described, the usual steam pressure control means 11 will function to limit the required pressure within 30 the system and a vacuum breaking means for the system such as a spring pressed ball valve indicated at 19 in Fig. 1 may be employed to prevent any radiator from creating a vacuum after condensation takes place. The steam pressure control switch 11 may be of any well known 35 type and is connected in series with the fuel burner motor. In like manner, the thermostatic switch 18 may be of any well known type and as shown is connected in series with line a and attached to the supply pipe 13, at its further 40 end is a return pipe 19' which will convey any water or condensation in the system back to the boiler, said pipe being provided as noted with a valve 19 for vacuum venting the system.

45 The control wiring diagram shown in the drawing is similar to that known in the trade as series #10 of the Minneapolis-Honeywell Manufacturing Company.

Many changes could be made in the construction and arrangement of parts, and many apparent widely different embodiments of the invention could be made without departing from the scope thereof, it is intended that all matter contained in the description or shown in 55 the accompanying drawing is as it is now intended to be arranged, but those skilled in the art may vary this arrangement without departing from the scope of the claims.

What I claim as new and desire to secure by 60 Letters Patent is:

1. Zone control means in combination with a steam heat system having a boiler, firing means therefor, radiators, a single-pipe line from the boiler to the radiators, a valved air vent means 65 on each radiator, a master thermostat control means for the firing means, and a boiler pressure responsive control means for the firing means; atmospheric temperature responsive means in operative connection with each air vent for controlling air discharge therefrom in accordance with local temperature conditions, and means responsive to temperature in the heating system for delaying action of the firing means control until the heating system temperature falls to a 70 predetermined point, and means in the heating 75

system for breaking radiator vacuum following each heating and subsequent cooling thereof.

2. Zone control means in combination with a steam heat system having a boiler, firing means therefor, radiators, a single-pipe-line from the boiler to the radiators, a valved air vent means on each radiator, a master thermostat control means for the firing means, and a boiler pressure responsive control means for the firing means; atmospheric temperature responsive means in 10 operative connection with each air vent for con-

trolling air discharge therefrom in accordance with local temperature conditions, and means responsive to temperature in the heating system at a position remote from the boiler for delaying action of the firing means control until the heating system temperature falls to a predetermined point, and means in the heating system for breaking radiator vacuum following each heating and subsequent cooling thereof.

CHARLES F. MAHONEY.
